UNITED STATES PATENT OFFICE.

EVAN EDMUNDS AND JOHN H. PENDLETON, OF PITTSBURG, PENNSYLVANIA, ASSIGNORS
TO JOHN F. HINCKLEY, OF PITTSBURG, PENNSYLVANIA.

MANUFACTURE OF ROLLS.

No. 905,857.

Specification of Letters Patent.

Patented Dec. 8, 1908.

Application filed March 9, 1906. Serial No. 305,086.

To all whom it may concern:

Be it known that we, EVAN EDMUNDS and JOHN H. PENDLETON, both of Pittsburg, in the county of Allegheny and State of Pennsylvania, have invented a certain new and useful Improvement in the Manufacture of Rolls, of which the following is a full, clear, and exact description, reference being had to the accompanying drawing, forming part 10 of this specification, in which—

Figure 1 is a perspective view illustrating our invention; Fig. 2 is a side elevation illustrating a modification thereof; and Fig. 3 is a longitudinal, vertical sectional view of 15 the modification shown in Fig. 2.

Like symbols of reference indicate like parts wherever they occur.

Our invention relates to an improvement in the manufacture of rolls and it consists 20 in so forming the wabbler or pinion and securing it to the body of the roll that it may be readily replaced. Heretofore in the manufacture of rolls where the pinions or wabbler have been formed integral with the 25 body of the roll, when the pinion breaks, the roll is useless and can only be thrown onto the scrap heap, thus causing an annual loss of thousands of dollars at every rolling mill plant.

30 We will now describe our invention so that others skilled in the art may employ the same.

Referring to Fig. 1 of the drawing, 2 represents the body of the roll, and 4, 4' the 35 necks which are on the roll at each end thereof. The neck 4' is adapted to journal in the housings of the roll. The neck 4 is adapted to receive the pinion or wabbler 5 which is slipped over the neck, said wabbler 40 being provided with a hole or socket therefor, and is brazed thereto with any suitable brazing material thus forming a pin and 45 socket joint between the roll and wabbler of great strength. Holes 6 extend longitudinally through the wabbler 5 and are adapted to register with holes 7 which are formed in the collar 3 of the roll. Suitable pins are passed through the hole 6 into the hole 7 and are secured by brazing. The 50 body of the roll 2 may be formed of cast iron while the wabbler or pinion 5 is preferably formed of steel, which is thus prolonging the life of the roll. Should any of the teeth of the wabbler or pinion 5 be broken, the 55 broken wabbler may be removed and a new

wabbler brazed to the roll in the manner already described. Should both the wabbler and the neck be broken from the body of the roll, the roll may be repaired by slightly turning down the collar 3 and fitting thereon 60 the wabbler 5' shown in Fig. 2, which has a socket portion 8 that fits over the collar 3'. In order to secure the socket 8 to the turned down collar 3', suitable brazing material is poured through the cavity 9 that extends 65 from the outer end of the wabbler 5' to the inner end of the socket 8 communicating with the cavity thereof.

The advantages of our invention will be appreciated by those skilled in the art. Instead of having to throw away the rolls when 70 the pinion thereof is broken the roll may easily be repaired.

Our invention may be employed in the manufacture of new rolls or it may be used 75 in repairing broken rolls in which the pinion originally was formed integral with the body of the roll.

Having thus described our invention, what we claim and desire to secure by Letters 80 Patent is:

1. A roll for rolling mills having a pinion or wabbler separate from the body portion of the roll, said body portion and pinion being united by means of a pin and socket 85 joint, and pins extending from said pinion into said body portion, and brazing material connecting said parts.

2. A roll for rolling mills having a pinion or wabbler separate from the body portion 90 of the roll, and means for connecting said parts, comprising a projection on one part extending into an opening or socket in the other part, and a layer of brazing material located between and uniting said connecting 95 means.

3. In combination, a roll or similar device, a second or additional device adjacent thereto, means for securing said devices together, the said means comprising a pin secured to 100 one of the said devices and extending into an opening in the other of said devices, another pin extending between said devices and into each of them, a layer of brazing material located between and connected to the adjacent surfaces of the said devices, and brazing material located between one of the said pins and the walls of the opening in which it is located, the said material being connected to the said pin and the said walls. 110

4. In combination, a roll or similar device, a second or additional device, and means for securing the said devices together, the said means comprising a pin secured to
5 one of the said devices and extending into an opening in the other of the said devices, a layer of brazing material located between and connected to the adjacent surfaces of the said devices, and brazing material located between and connected to the pin and

the walls of the opening in which the said pin is located.

In testimony whereof, we have hereunto set our hands.

EVAN EDMUND.
JOHN H. PENDLETON.
